Patented Apr. 19, 1960

187,725

MOTORCYCLE SADDLE BAG AND TAIL LIGHTS UNIT

Ted Zbikowski, Detroit, Mich., assignor to Joseph
Buegeleisen Company, Detroit, Mich.

Application September 25, 1959, Serial No. 57,691

Term of patent 14 years

(Cl. D90—3)

FIG. - 1

FIG. - 2

Des. 187,725

PAGE 2

FIG. - 3

FIG. - 4

FIG - 5

Fig. 1 is a right side elevational view of a motorcycle saddle bag and tail lights unit showing my new design;

Fig. 2 is a front elevational view thereof;

Fig. 3 is a rear elevational view thereof;

Fig. 4 is a top plan view thereof; and

Fig. 5 is a perspective view thereof taken from the left side.

This application is a continuation in part of my earlier application, Serial No. D. 53,084, filed October 22, 1958.

I claim:

The ornamental design for a motorcycle saddle bag and tail lights unit, as shown.
